UNITED STATES PATENT OFFICE.

DAVYDD C. HUGHES, OF CHICAGO, ILLINOIS, ASSIGNOR, BY MESNE ASSIGNMENTS, TO
ADDRESSEOGRAPH COMPANY, OF CHICAGO, ILLINOIS, A CORPORATION OF ILLINOIS.

DATING-MACHINE.

1,152,637.

Specification of Letters Patent.

Patented Sept. 7, 1915.

Application filed October 8, 1910. Serial No. 586,057.

To all whom it may concern:

Be it known that I, DAVYDD C. HUGHES, a citizen of the United States, and resident of Chicago, Cook county, Illinois, have invented a certain new, useful, and Improved 5 Dating-Machine, of which the following is a full, true, clear, and exact description, such as will enable others skilled in the art to which it appertains to make and use the 10 same.

My invention relates to improvements in so-called printing and addressing machines, and has special reference to improvements whereby the letters, statements, circulars 15 and the like printed by the machine will be dated at the time that they are printed.

The object of my invention is to so improve the construction and equipment of machines for addressing, and printing letters, statements, circulars, and the like that 20 the same may be dated simultaneously with their production, and in a manner that will give them the appearance of having been wholly written or produced by a typewriter 25 machine.

Another object of my invention is to provide a dating mechanism or device upon or in connection with an addressing machine, and which shall be readily adjustable with 30 relation to the other parts of the machine, to the end that the position of the date upon the printed sheet may be varied to suit the requirements of the body of printed matter.

A further object of my invention is to 35 provide a date printing attachment of rotary character which shall be self-contained and capable of being attached to or removed from addressing and printing machines having rotary parts adapted to receive the attachment.

As before intimated the particular object of the invention is to provide a machine for simulating the work of ordinary typewriting machines, and which, like the typewriter, shall be characterized by an inked 45 ribbon through which the type are impressed upon the paper, and in this connection it may be stated that my further purpose is to provide an improved addressing and dating machine using a plurality of so-called address plates, and in which the printing operation shall be performed with a minimum quantity and expenditure of ink 50 fabric.

Still further objects of my invention will 55 appear hereinafter.

My invention consists generally in an addressing machine utilizing a plurality of address plates, and including a dating device for printing a date upon each article 60 which is addressed.

My invention also consists in a letter printing, addressing and dating machine adapted to perform at each operation all 65 three of the functions mentioned.

These and other features of my invention will be more readily understood by reference to the accompanying drawings in which I have illustrated a preferred form of 70 my invention.

These drawings constitute a part of this specification, in which drawings—

Figure 1 is a top plan view of the forward portion of a printing machine various parts of which are broken away to expose 75 the dating mechanism to view; Fig. 2 is a transverse vertical section on line 2—2 of Fig. 1; Fig. 3 is a vertical longitudinal sectional view taken on line 3—3 of Fig. 1; Figs. 4 and 5 are sectional views of the 80 dating mechanism taken substantially on line x—x of Fig. 2, these views showing the type in and out of the printing plane respectively; Fig. 6 is a view of that portion of the dating mechanism included between 85 the parallel dotted lines in Fig. 5 looking in the direction of the arrows; Fig. 7 is a top view of the type holder; Fig. 8 is a fragmentary view of the carrier showing the type holder in side elevation; Fig. 9 is 90 a sectional view taken on line 9—9 of Fig. 8.

My invention relates especially, but not necessarily, to that class of printing machines of the character employed for addressing letters, envelopes, cards and the like, 95 for duplicating letters and circulars; more particularly in imitation of ordinary type-written matter. It is desirable that these machines be arranged to date the letters, circulars, statements and the like in the same 100 operation that the rest of the printing is done. The date, however, is a variable factor in the complete make up of a letter or circular, and any mechanism employed for performing the dating operation must necessarily be conveniently and quickly adaptable to the changes in dates as required 105 without disturbing the adjustment of the

other parts of the machine. In addition to this, there are several features which are desirable in a practical dating mechanism, such as adjustability of such mechanism for 5 the purpose of placing the impression on the sheet of paper in its proper position. This requirement necessarily follows from the fact that the different articles which are to be printed vary considerably in size, depending upon the nature of the work to be 10 done. I have provided a dating mechanism in connection with printing machines of this character which meets all of these requirements in a single and satisfactory manner. The machine with which I have chosen 15 to illustrate my invention is of the "Rogers" type where successive pieces of printable material are fed to a rotary printing mechanism by which they are printed and discharged. The following explanation of the 20 nature and functions of my invention will clearly point out that the invention is not necessarily limited to the particular machine illustrated in the drawings and that, 25 by suitable modification, it may be made applicable to various other printing machines or mechanisms without departing from the spirit of the invention.

The machine illustrated in the drawings 30 is known as a multi-printing and addressing machine. It is of the class wherein the date, superscription or address, salutation and body of the letter are printed in a single operation as the successive sheets of paper 35 are fed to the printing mechanism.

The machine has a rotary printing mechanism comprising two large drums 1 and 2 co-axially mounted upon a shaft 3 and, in the preferred construction, independently 40 rotatable together with a platen or pressure roll 4 of a length substantially equal to the combined length of the two drums. This roll co-acts with the drums to print the pieces of paper, cards, or envelopes 5" which 45 are successively fed at timed intervals from the feed mechanism 5.

In the particular machine illustrated it is 50 desirable to reduce the size of the parts as much as possible, and to this end I provide a comparatively small type plate drum 1 and letter drum 2. With a small type plate drum, however, it is not advisable to print at each revolution of the drum, since the 55 wear and tear on the machine and plates would be too great; therefore, I prefer to so proportion the parts of the machine that an address plate will be brought forward to the printing mechanism at each second revolution of the plate drum. Thus it is evident 60 that for each printing operation the plate drum must make two revolutions while the letter drum is making one. I prefer to rotate the plate drum at a constant speed and to vary the speed of the letter drum to suit 65 the conditions just described. For this rea-

son I connect the plate drum directly to the shaft of the machine while the letter drum is rotatable on the shaft and is driven by a suitable differential gear mechanism 2' to bring about the above variations in the 70 speed of the letter drum. It will be understood, of course, that during the printing operation the peripheral speeds of the letter drum and the type plate drum are the same even though the type plate drum is smaller 75 in diameter than the printing periphery of the letter drum. The type plate drum is made smaller in diameter than the letter drum in order to accommodate the type plate, which is adapted to pass over the same 80 during the printing operation and in order that the printing surface of the type plate may lie in the same plane as the printing surface of the letter drum. At the same time, while the type plate drum is smaller 85 in diameter, the peripheral speed of the type plate on the same must be the same as the peripheral speed of the type drum in order that the type plate will move at the same 90 surface speed as the surface speed of the letter drum.

The printing mechanism is rotatably mounted in the side members 6 of a suitable supporting framework which maintains the 95 various parts in co-operative relation to each other. A crank or handle 7 is secured to one end of the shaft and serves as a means of operating the machine. The large drum 2 is provided with a plurality of type 100 grooves on its periphery in which grooves the type 8 are set up to represent the body of a letter or circular. This drum is referred to as the letter or body drum. The drum 1 is known as the type plate drum. It co-acts 105 with the pressure roll to press the type plates and pieces of paper into printing engagement as they pass through the space between said drum and roll. The type plates 9 are individual in character each usually 110 representing a name and address. They are brought forward at intervals along the guide or bed plate 10 by a conveyer chain 11 leading from the magazine (not shown) at the rear of the machine in which they are 115 initially stacked. The forward end of the conveyer chain is co-axial with the drum 1 and is carried upon a sprocket wheel 13.

The type plates are moved through the space between, and are pressed by, the roll 120 and drum, being thence discharged into a chute 14 by which they are directed into a receiver (not shown) in the lower part of the machine. Figs. 2 and 3 show a type plate 125 which has passed the printing mechanism and is on the way downwardly to the receiver.

The ink is supplied to the type or the type plates and to the type on the letter drum 2 by means of a wide inked fabric or ribbon 130 extending through the space between the

letter drum and the platen roll. This ribbon, as shown in Figs. 1, 2 and 3 is held above the type in a tensioned condition by suitable holders 15' and 15'', these holders 5 acting to intermittently feed the ribbon through the printing mechanism in time for the printing operations. The ribbon, as clearly seen, is sufficiently wide to overlap part of the type plate drum so as to supply 10 ink to the type upon the type plates. As the articles to be printed are successively fed downwardly along the guide plate 5 they pass above the ribbon through the space in the printing mechanism, and since the type 15 are below the ribbon they print through the ribbon and as a result the imprints resemble that done by the ordinary typewriter.

For the purpose of accommodating the dating mechanism the major portion of the 20 type plate drum is grooved or made smaller in diameter, as more clearly shown in Fig. 2, so that the dating mechanism lies principally within the periphery of the drum and hence within the printing plane or level. 25 This portion of the drum is made wide enough to allow considerable adjustment of the dating mechanism in an axial direction so that the date may be positioned at different heights on the letter. The dating mechanism, as shown, may be placed on either side of the conveyer chain sprocket wheel 13.

I prefer to make the dating mechanism in the nature of a self-contained structure attachable or detachable as a whole, but it is 30 clearly obvious that it may be constructed as a part of the printing mechanism if desired. It is rotary in character and preferably associated with the type plate drum of the printing mechanism. For this reason I 35 provide an arc-shaped carrier or frame 16 extending substantially half around the smaller periphery 1' of the drum and conformed on its inner and outer edges to the curvature thereof. By constructing the carrier in this manner it is adjustable circumferentially of the drum and independently thereof so as to position the type holder 17, which it carries, relatively to the body and superscription of a letter, statement or the 40 like; thus making it possible to place the date in various positions on the edges of the sheet of paper. The articles to be printed are preferably fed so that the printing begins with the left hand margin and the address or superscription and also the salutation begin at this point. Since the date is 45 usually close to the right-hand margin of the article it follows that it will be printed toward the end of the printing operation. 50 The reason then is obvious for arranging the dating mechanism so that it is adjustable because the printing of the date may be adjusted to lag the proper amount behind the beginning of the printing operation of the 55 article.

The frame or carrier has an extension 19 on one of its ends which serves as a means for clamping the frame in its adjusted position on the drum. Like the frame, it is conformed to the periphery of 70 the drum, so that the frame and extension together embrace the drum for more than half of its periphery. This extension is pivoted at 21 to the frame, as clearly shown in Figs. 4 and 5, for the purpose of permitting 75 the removal of the dating device. It is operated by means of the screw 22 carried in the tail 23 and acting against the end of the frame. This arrangement enables the dating mechanism to be conveniently removed 80 from the drum or clamped in position thereon by simply turning the screw in the proper direction to tighten or loosen the clamp.

The parts of the machine depicted in the drawings are so proportioned that as before mentioned a type plate is brought forward at every second revolution of the type plate drum. The particular embodiment of my invention herein described is therefore constructed to adapt it to this condition. The 85 type holder or type block 17, as will be seen, is peculiarly shaped. It is curved at its upper and lower ends, the arcs of curvature being concentric to the circumference of the drum. This holder is radially movable so 90 as to carry the type 24 into or out of the printing plane, as shown in Figs. 5 and 4, respectively, the holder being guided in its movement by the sides of the carrier or frame 16. Two spiral springs 25 are anchored respectively to the bottom of the frame and to opposite edges of the type holder and constantly tend to maintain the holder in its lower or non-printing position. For the purpose of shifting or moving 95 the type holder of the dater into and out of the printing plane I provide a cam 26 which co-acts with a small roller 27 on the type holder. This cam is formed, as shown, to alternately raise the type holder in to printing position and withdraw it therefrom, so 100 that the type holder is raised into printing position during the revolution of the drum in which a type plate is passing through the printing mechanism, and is in its depressed or withdrawn position out of the printing plane, during the revolution of the drum wherein no type plate is passing through the printing mechanism. In other words, the 105 type holder is in its printing position every 110 second revolution of the drum. The cam is mounted upon a small shaft 28 journaled in the sides of the frame and this shaft carries a small toothed wheel which is actuated through the medium of a long pawl 30 by the bell crank lever 31 pivoted at 32 to the side portions of the carriage. A small spring 33 constantly holds the pawl in engagement with the toothed wheel. The 115 spring also holds the longer arm of the bell 120 125 130

4
crank lever 31 in its operative position, that is, in a position wherein it projects beyond the surface or periphery of the drum. During the rotation of the drum this arm strikes 5 the upper platen roll and actuates the pawl to shift the cam around one point or step at a time thereby alternately shifting the type holder into and out of printing position. This operation occurs in advance of 10 the arrival of the type holder at the printing position, as is evident by the direction of rotation of the drum.

One of the objects of my invention is to produce printed articles in imitation of the 15 ordinary typewritten letters and to make the printed date consistent in this respect with the rest of the printed article, I print the date through an inked fabric or ribbon. Under certain conditions I could obviously 20 widen the main ribbon 15 sufficiently to lap the dating type. But it frequently is the case that the date and address only are printed and not the body of the article, hence it would be quite expensive and un- 25 economical to use the main ribbon. Furthermore, in this particular machine the ribbon 15 has a reciprocating progressive movement and it might not be moving in the proper direction at the instant the date is being 30 printed. I therefore provide a separate and independent inker for the dating mechanism. This consists of a small inked fabric or ribbon 35 through which the type print. This ribbon extends along the face of the 35 type (as shown in Figs. 4 and 5) and is stretched between and wound upon two reels or spools 36 and 37 disposed on opposite sides of the type holder, the reels being 40 removably journaled in the sides of the frame. In order that the ribbon may present a relatively new inked surface for each 45 impression of the type, I rotate one of the reels so that the ribbon is pulled forward or moved a slight amount with each revolution 50 of the drum. One of the flanges of the reel 36 is toothed to form a gear and this meshes with a small pinion 37 of a reducing train 55 of intermeshing gears. The gears of this train are suitably journaled in the sides of 60 the frame. The other end of this train of gears has a toothed wheel or ratchet wheel 38 which is actuated by means of a small 65 spring pressed pawl 39 carried upon the longer arm of the bell crank lever 31 so that each time the bell crank lever strikes the 70 roll it steps the toothed wheel around one tooth and, through the medium of the train of gears just mentioned, rotates the reel 36 and winds the ribbon on said reel a proportionate amount. The reason I have 75 provided the speed reducing train of gears is that the rate at which the ribbon moves is just sufficient to enable all of its inked surface to be completely used and it is practically worn out. This eliminates the ne-

cessity of shifting the ribbon back and forth and hence provides a much simpler structure. A drag or brake spring 40 acts on the edges of the reel 37 for the purpose of constantly maintaining the ribbon under tension and keeping it properly stretched in 70 position. The ribbon is guided onto the type by means of a small guide 41.

The type 24, which are preferably used with this mechanism, are metallic and have 75 grooves 43 in their side edges as shown in Fig. 9. They are set in a type channel 44 provided in the upper curved face of the type holder. This channel has overhanging flanges 45 which register with the grooves 80 in the side faces of the type to lock the type in the channel. For the purpose of permitting the type to be placed in this channel or removed therefrom, I provide a vertical slot 46 in the side face of the type holder, 85 this slot being deep enough to cut away a portion of one of the side walls of the channel. A flat spring 47 (Figs. 7 and 8) normally maintains this opening in the channel wall closed, but, as shown, it may be sprung 90 away sufficiently to permit the entrance or removal of the type.

It is sometimes desirable that a printed impression be made for each revolution of the drum. For this purpose I provide holes 95 49 in the type holder and also in the sides of the frame. These holes register when the type holder is in its raised or printing position, and by inserting pins therein the type holder may be held in said position. 100

It is also desirable at times to dispense with the use of the dating mechanism without removing it from the drum. For this purpose I provide holes 50 and 51 in the bell crank lever 31 and the sides of the 105 frame, these holes being adapted to register when the lever is in its depressed or non-operative position. By placing a pin in the holes when they are registered with each other the entire mechanism may be placed 110 in an inactive condition, the effect being the same as if the dating mechanism were removed.

It is to be noted that my invention in a 115 sense constitutes an auxiliary printing mechanism co-acting with the main printing mechanism of the machine, and if desired may be permanently related to said main printing mechanism.

While I have shown one embodiment of 120 my invention for the purpose of an understanding thereof, I do not desire it to be limited to the particular structure since it is obvious to those skilled in the art that my invention is capable of various modifications without departing from the spirit thereof.

I claim:

1. An addressing machine of the kind 130 wherein type plates are periodically pressed

into printing engagement with the pieces of printable material fed to the machine, in combination with mechanism for presenting an inked ribbon between each plate and piece of material during the interval of pressure thereupon, a dating mechanism, an inked ribbon co-acting therewith, and actuating means for said dating mechanism operable to impress a date upon the pieces of material through said co-acting inked ribbon and at a pre-determined time interval following the addressing operation.

2. In a machine of the class herein described, a printing drum, in combination with a co-axial type plate drum, and a dating mechanism positioned on and rotatable in time with said type plate drum, said mechanism being independently and rotatably adjustable with respect to said drum.

20 3. A machine of the class described, a printing drum, and a co-axial type plate drum rotatable in the same direction, a dating mechanism co-axial with said drums and rotatable therewith, a wide inked ribbon common to said drums and movable therewith, and a narrow independent inked ribbon individual to said dating mechanism.

4. In a machine of the class described, a printing drum and a type plate drum co-axially arranged and rotatable at the same peripheral speed during the printing operation, a dating mechanism rotatable upon the same axis as said drums and adjustable relatively thereto for dating articles fed to the machine at a pre-determined instant in the complete printing operation, a broad inked ribbon co-acting with and common to said drums, and an independent inked ribbon individual to and co-acting with said dating mechanism.

5. In a machine of the class described, a printing drum and a type plate drum co-axially arranged and rotatable at the same peripheral speed during the printing operation, a dating mechanism rotatable with and upon the same axis as said drums, said dating mechanism being adjustable relatively to the drums for dating articles fed to the machine at a pre-arranged instant in the complete printing operation, a broad inked ribbon co-acting with and common to said drums, an independent, comparatively narrow, inked ribbon individual to and movable with said dating mechanism, and a pressure roll co-extensive with and operable to press the articles to be printed upon said drums and dating mechanism.

6. In a machine of the class described, a printing drum and a type plate drum arranged co-axially and rotatable at the same and relatively different speeds, a dating mechanism upon and rotatable with said type plate drum, a wide inked ribbon co-acting with and supplying ink to said drums, and a narrow inked ribbon indi-

vidual to and rotatable with said dating mechanism.

7. In a machine of the class described, a printing drum and a type plate drum of less diameter co-axially arranged and rotatable with said printing drum, means for feeding type plates in succession to said type plate drum, a dating mechanism rotatable with said type plate drum, a broad inked ribbon supplying ink jointly to said printing drum and to the plates on said type plate drum, a comparatively narrow independent inked ribbon individual to said dating mechanism, and a pressure roll common to said drums and dating mechanism.

70 8. In a machine of the class described, a rotary printing mechanism comprising a type plate drum and a co-operating pressure roll, means for feeding type plates successively to said printing mechanism, a dating mechanism concentrically arranged with respect to and rotatable with said type plate drum, said dating mechanism being adjustable relatively to said type plate drum for positioning it in a definite printing relation to said type plate drum.

85 9. A printing machine of the kind wherein successive pieces of paper are passed through a rotary printing mechanism under pressure and discharged, in combination with means for dating said pieces of paper, comprising a type member and type carried thereby, said member being carried by and circumferentially and longitudinally adjustable independently of the printing mechanism for pre-determining the position of the printed impression, and mechanism intermittently actuated by the printing mechanism for moving said type member and its type into or out of the printing 100 position.

10. A printing machine of the kind wherein successive pieces of paper are passed through a rotary printing mechanism under pressure and discharged, in combination with dating means, comprising a type member and type carried thereby, said member being mounted upon and circumferentially and axially adjustable independently of the printing mechanism for 110 pre-determining the position of the printed impression, and mechanism movable with said member intermittently actuated by the printing mechanism for moving said type member to position the type in or out of 115 the printing plane in advance of the arrival of the type to the printing position.

11. A printing machine having a rotary printing mechanism, and having means for printing a date, comprising a member and 125 type carried thereby, a supporting frame therefor conformed to the rotary parts of the printing mechanism and circumferentially adjustable with respect thereto for positioning the printed impression, and 130

mechanism coöperating with the printing mechanism for shifting the type carrying member into printing position.

12. In a printing and addressing machine, 5 the combination of printing mechanism, a type carrying member normally carried in inoperative position by said printing mechanism, said member being adjustable circumferentially of said printing mechanism, 10 means for intermittently actuating said member to position the type carried thereby in the printing plane of said printing mechanism, an inked ribbon, and means for shifting said ribbon at each actuation of 15 said type carrying member.

13. An attachment for use with printing machines and the like, comprising a type carrying member having a relative movement with respect to the printing mechanism for varying the position of the impression, said member normally maintaining the type below the printing plane, an inked ribbon supplying ink to the type, and mechanism intermittently actuating said 25 member to move the type into the printing plane and simultaneously shifting said ribbon to present a relatively new surface thereof.

14. A printing machine having a rotary printing mechanism in combination with a separate and independent mechanism removably attachable to and having a printing relation variable with respect to said rotary printing mechanism, type carried by 30 said independent printing mechanism, and an inking device for said type carried by said independent printing mechanism.

15. A self-contained, unitary dating device for use with printing machines having 40 printed mechanisms of the rotary type, comprising a type carrier removably attachable to the printing mechanism of the machine and having a variable printing relation to said printing mechanism for positioning its printed impression, and an inker carried by said carrier and supplying ink 45 to the type.

16. A dating device for printing machines comprising in a self-contained unitary structure 50 an arc-shaped carrier, and means detachably fastening said carrier to the printing mechanism of the machine, a type holder on said carrier movable to present the type in printing position or to withdraw the type therefrom, mechanism actuating said holder and an inking ribbon.

17. A dating device for printing machines comprising in a self-contained unitary structure 55 an arc-shaped carrier and means removably securing said carrier to the printing mechanism of the machine, a type holder on said carrier movable to present the type in printing position or to withdraw the type therefrom, and a shifting mechanism intermittently actuating said holder.

18. A dating attachment for printing machines comprising in a self-contained unitary structure a frame, a type receiving and holding part, a shifting mechanism intermittently actuating said part to bring the 70 type into the printing line and withdraw it therefrom, and means securing said frame to the printing mechanism of the machine, but permitting a relative movement to position the date on the material upon which 75 the impression is made.

19. A dating mechanism for printing machines having rotary printing mechanisms, comprising a member and type carried thereby, a supporting frame therefor conformed to the rotary parts of the printing mechanism and circumferentially adjustable with respect thereto for positioning the printed impression, a cam for shifting said type member into or out of the printing position, and mechanism carried by said frame in co-active relation to the pressure parts of the printing mechanism for operating said cam.

20. A dating mechanism for printing machines having rotary printing mechanism, comprising a member and type carried thereby, a frame for said member conformed to and mounted on the printing mechanism and circumferentially adjustable with respect 95 thereto for positioning the printed impression, an inked ribbon movable along the face of the type, and mechanism carried in said frame and co-acting with the rotary parts of the printing mechanism for radially shifting said type member into or out 100 of printing position and simultaneously moving said ribbon.

21. A dating mechanism for printing machines of the kind wherein successive pieces 105 of paper are passed through printing rolls and discharged, comprising a frame and a radially movable type holder carried thereby, said frame being conformed to one of the printing rolls and circumferentially adjustable independently thereof for positioning the imprint, and mechanism having a part adapted to strike another of the printing rolls for actuating said mechanism to intermittently move the type member and thereby depress the type out of the printing plane.

22. A dating mechanism for printing machines of the kind wherein successive pieces 115 of paper are passed through printing rolls and discharged, comprising a frame and a radially movable type holder carried thereby, said frame being conformed to one of the printing rolls and circumferentially adjustable independently thereof for positioning the imprint, mechanism having a part adapted to strike another of the printing rolls for actuating said mechanism to intermittently move the type member and thereby drop the type face below the printing 120 125 130

plane, holders carried by said frame, and an inked ribbon lying along the face of said type and stretched between said holders, said mechanism being adapted to actuate 5 one of said reels simultaneously with the movement of the type holder.

23. A dating mechanism for printing machines having rotary printing rolls, comprising an arc-shaped frame and a movable 10 type holder carried thereby and containing type, said frame being circumferentially and axially adjustable independent of the printing roll for positioning the imprint, means detachably securing said frame in its adjusted position, a cam for shifting said type holder into and out of printing position, a reel on each side of said type holder, an inked ribbon mounted thereon and extending along the face of the type, a part projecting beyond the face of said printing roll and adapted to intermittently strike a correlated printing roll, and mechanism actuated by said part for shifting said type holder and for simultaneously rotating one 20 of said reels to shift the ribbon.

24. In a device of the character described, the combination with a rotary printing mechanism comprising a rotary drum having type secured on the face thereof and a 30 second rotary drum over which type plates are arranged to pass, of a self-contained unitary mechanism associated with said mechanism and adapted to rotate therewith, comprising a type-holding member, an inking 35 ribbon and means for intermittently moving said ribbon to cause the same to present a new surface to the type.

25. In a device of the character described, the combination with a rotary printing 40 mechanism comprising a rotary drum having type secured on the face thereof and a second rotary drum over which type plates are arranged to pass, of a self-contained unitary dating mechanism associated with said printing mechanism and adapted to rotate therewith, comprising a type-holding member, an inking 45 ribbon and means for moving said ribbon to cause the same to present a new surface to the type after each impression.

26. In a device of the character described, the combination with a rotary printing mechanism comprising a rotary drum having type secured on the face thereof and a 50 second rotary drum over which type plates are arranged to pass, of a self-contained unitary dating mechanism associated with said printing mechanism and adapted to rotate therewith, comprising a type-holding member, an inking 55 ribbon and inking ribbon supporting means.

27. In a device of the character described, the combination with a printing mechanism comprising a rotary drum having type secured on the face thereof and a second ro-

70 tary drum over which type plates are arranged to pass, of a self-contained unitary dating mechanism associated with said printing mechanism and movable therewith, comprising a type-holding member, an inking ribbon and means for intermittently moving said ribbon to cause the same to present a new inking surface to the type.

28. In a device of the character described, the combination with a rotary printing 75 mechanism comprising a rotary drum having type secured on the face thereof and a second rotary drum over which type plates are arranged to pass, of an adjustable self-contained unitary dating mechanism associated with said printing mechanism and adapted to rotate therewith, comprising a type-holding member and an inking ribbon and means for intermittently moving said ribbon to cause the same to present a new 80 surface to the type.

29. In a device of the character described, the combination with a rotary printing mechanism comprising a rotary drum having type secured on the face thereof and a 90 second rotary drum over which type plates are arranged to pass, of a removable self-contained unitary dating mechanism associated with said printing mechanism and adapted to rotate therewith, comprising a 95 type-holding member, an inking ribbon and means for intermittently moving said ribbon to cause the same to present a new surface to the type.

30. In a device of the character described, the combination with a rotary printing mechanism, of a self-contained unitary dating mechanism associated with said printing mechanism and adapted to rotate therewith, comprising a type holder and an inking 100 ribbon, and means for rendering said dating mechanism inoperative without removing the same.

31. In a device of the character described, the combination with a printing drum having the subject-matter to be printed set up 110 on said drum in lines extending circumferentially thereof, and a dating mechanism rotatable with said drum having the date set up thereon in a line parallel with the subject-matter on the drum and circumferentially adjustable.

32. In a device of the character described, the combination of a printing drum having the subject matter to be printed set up thereon, a dating device carried by and adjustable circumferentially of said drum, and mechanism for controlling the radial position of said dating device.

33. In a mechanism of the character de- 125 scribed, the combination of a printing drum having printing characters arranged on its periphery, and a dating device adjustable circumferentially of and rotatable with said drum and movable radially of said drum.

34. In a device of the character described, the combination of a rotatable drum having printing characters disposed on its periphery, a dating device rotatable with said drum and adjustable circumferentially of the drum, and means for intermittently moving said dating device radially of the drum.

In testimony whereof, I have hereunto set my hand this 27th day of September, 1910, in the presence of two subscribing witnesses.

DAVYDD C. HUGHES.

Witnesses:

EDGAR F. BEAUBIEN,

JOHN R. LEFEVRE.
